(57) **CLAIM**

The ornamental design for a containerizing and watering device, as shown.

DESCRIPTION

FIG. 1 is a perspective view of a containerizing and watering device showing my new design in an exploded condition; FIG. 2 is a top view of the bottle shown separately for ease of illustration; FIG. 3 is a front view of FIG. 2; FIG. 4 is a side view of FIG. 2; FIG. 5 is a rear view of FIG. 2; FIG. 6 is a bottom view of FIG. 2; FIG. 7 is top view of a containerizing and watering device in assembly condition; FIG. 8 is side elevational view of FIG. 7; FIG. 9 is a top view of the interior container shown separately for ease of illustration; FIG. 10 is a front view of FIG. 9; FIG. 11 is a rear view of FIG. 9; and, FIG. 12 is a bottom view of FIG. 9. The broken line shown in the drawing is for illustrative purposes only and forms no part of the claimed design.
